DOOR CONSTRUCTION

Oscar Roy Klein, 740 Custer, Salina, Kans.
Filed Oct. 21, 1960, Ser. No. 64,072
7 Claims. (Cl. 160—113)

This invention relates to a sliding and adjustable door construction, and more particularly to a door construction for railroad freight cars or the like.

The primary object of this invention is to provide a door construction which is especially suitable for use with freight cars that are used for transporting or hauling bulk material such as grain, and wherein according to the present invention the doors are slidably connected to tracks, and wherein the tracks can be adjusted back and forth in the freight car so as to insure that there will be a tight fit or seal between the sliding doors and the openings in the freight car so that leakage or spillage of grain or other material will be eliminated or prevented, and wherein there is also provided for each door a hingedly mounted closure or panel which can be readily opened for any desired purpose.

Still another object is to provide such a door construction which includes means for adjusting the tracks that slidably support the doors, the doors consisting of a plurality of sections which are hingedly connected together, and wherein there is provided a means for retaining or maintaining the closure of each door in opened or closed position as desired, and wherein there is also provided a manually operable means for moving or shifting the tracks and doors so that for example a door can be pulled up tight against the sills or posts in the freight car or other member on which the door construction of the present invention is being used.

Still another object is to provide such a door construction that is economical to manufacture and efficient in operation and which is rugged in structure and foolproof in use.

These and other objects of the invention will become apparent from a reading of the following specification and claims, taken with the accompanying drawings, wherein like parts are referred and indicated by like reference characters and wherein:

FIGURE 1 is a fragmentary side elevational view illustrating a freight car equipped with a door construction according to the present invention, and with parts broken away in section.

FIGURE 2 is a vertical sectional view taken at right angles to the view shown in FIGURE 1 and FIGURE 2 being a sectional view taken through both doors of the freight car and wherein one of the doors is in lowered position while the other door is in raised or elevated position.

FIGURE 3 is a sectional view taken on the line 3—3 of FIGURE 2.

FIGURE 4 is an enlarged elevational view illustrating certain constructional details of the closure in the bottom of a sliding door together with the actuating means therefor.

FIGURE 5 is a sectional view taken on the line 5—5 of FIGURE 4.

FIGURE 6 is a sectional view taken on the line 6—6 of FIGURE 4.

FIGURE 7 is a sectional view taken on the line 7—7 of FIGURE 4.

FIGURE 8 is a sectional view taken on the line 8—8 of FIGURE 4.

FIGURE 9 is a perspective view showing one of the anchor members for slidably supporting the upper end of the track.

FIGURE 10 is a perspective view showing a part of the locking mechanism for the door closure or panel.

2

FIGURE 11 is a fragmentary perspective view illustrating certain constructional details of the locking mechanism for the closure.

FIGURE 12 is a sectional view taken through the anchor member and portion of the track shown in FIGURE 9.

FIGURE 13 is a fragmentary elevational view illustrating the members on the support member which slidably support the upper sections of the tracks.

FIGURE 14 is a fragmentary plan view illustrating the winch and cable mechanism for raising and lowering the doors.

FIGURE 15 is a diagrammatic view illustrating the winch and cable mechanism.

FIGURE 16 is a fragmentary horizontal sectional view illustrating a modification wherein the present invention is shown being used in a construction wherein the tracks are not lined up with respect to each other.

Referring in detail to the drawings, the numeral 30 indicates a portion of a conventional freight car or other hollow member which may be mounted on the usual railway wheels so that the freight car can travel along rails and wherein the freight car is adapted to be used for hauling or handling bulk material such as grain. The freight car 30 includes a horizontally disposed floor 31 as well as vertically disposed spaced parallel side walls 32 which are provided with openings 33 therein, and these openings 33 can be used for removing grain from the freight car or else the openings can be used as a means for permitting the grain or other bulk material to be loaded into the freight car. The freight car 30 further includes a top 34, FIGURE 2. The numeral 35 designates each of a pair of spaced parallel vertically disposed posts, and the posts 35 are arranged on opposite sides of each of the openings 33. The numerals 36 and 37 indicate horizontally disposed crosspieces which are arranged in the freight car 30 above the posts 35.

The numeral 38 indicates a first pair of tracks, and the numeral 39 indicates a second pair of spaced apart tracks which each have the same general construction. The tracks 38 include horizontally disposed upper sections 40 as well as the intermediate rounded sections 41 and the tracks 39 also include lower vertically disposed sections 42.

The second tracks 39 embody horizontally disposed upper sections 43, rounded or arcuate intermediate sections 44 and lower vertically disposed sections 45.

The numeral 46 designates each of a pair of anchor members which are affixed to the crosspiece 37, and the anchor members 46 have end portions of the tracks 38 slidably supported therein, FIGURE 9. Each of the anchor members 46 is U-shaped in cross section, FIGURE 12, and each anchor member 46 embodies portions 47 and 48, the portion 48 being provided with slots 49, and securing elements 50 extend through the slots 49 and are connected to the sections 40 of the tracks 38. Flanges or ears 51 on the ends of the anchor members 46 are fastened as at 52 to the crosspiece 37.

The numeral 53 indicates a support member which includes a horizontally disposed top portion 54 that is suspended from the top 34 of the freight car 30 by means of hangers 55, FIGURE 1. The support member 53 further includes vertically disposed depending end portions 56 as well as diametrically opposed horizontally arranged bottom portions 57. Clips 58 depend from the top portion 54 of the support member 53 and are secured thereto in any suitable manner, and the clips 58 provide a slidable support for the sections 40 of the tracks 38. As shown in the drawings there is further provided brackets 59 on the upper inner ends of the portions 57, and the brackets 59 provide a slidable support for the upper sections 43 of the tracks 39.

There is further provided a pair of adjustable or movable doors 60, and one of the doors 60 is provided for the pair of tracks 38, and another door is provided for the pair of tracks 39 and these doors 60 are adapted to each have a similar construction as shown in the drawings. Each door 60 embodies a plurality of sections 61 which are hingedly connected together as at 62.

A winch mechanism 69 is provided for raising and lowering each door 60, and one of the winch mechanisms 69 is shown in detail in FIGURES 14 and 15 wherein the numerals 64 and 65 indicate sheaves or drums which have cables 63 and 63' connected thereto, and there is also provided drums 67 and 68 which have cables 66 and 66' thereon. The cables 63, 63' and 66, and 66' are adapted to be trained over guide pulleys such as the guide pulleys 70 and these cables are suitably affixed as at 77 to portions of the doors 60. A hand wheel 71 is connected to an end of a rotary shaft 72, and the shaft 72 has a small gear 73 thereon which meshes with a larger gear 74, and the gear 74 is suitably affixed to a tubular member 75, the tubular member 75 having the drums 64, 65, 67 and 68 affixed thereto. Vertically disposed panels 81 and 82 are mounted beneath the freight car 30, as for example as shown in FIGURE 1, and in FIGURE 14, and the shaft 72 as well as the tubular member 75 is rotatably supported by the panels 81 and 82. A dog 83 engages a gear 78 for preventing accidental movement of the winch mechanism, and a spring member 84 is provided for urging or biasing the dog 83 into engagement with the gear 78. By properly rotating the hand wheel 71, a door 60 can be raised and lowered as desired as later described in this application. The shaft 72 is provided with an outer end portion 79 which may be of square shape so as to permit connection to a driving motor or the like as for example when the shaft is to be motor operated instead of being manually turned.

A means is provided for permitting movement of the doors 60 along the tracks 38 and 39, and this means comprises rollers 86 which engage the tracks, and the rollers 86 are suitably secured to the doors 60 by means of pins or studs 87, FIGURE 5.

There is further provided U-shaped base members 88 which are secured to the lower inner portions of the posts 35, and the base members 88 include a back portion 89 as well as side portions 90, and a pin 91 extends between the side portions 90 and each base member 88. An apertured lug 165 is secured to the lower end portion of each track, and the lug 165 is slidably mounted on a pin 91 and this construction permits the tracks to be adjusted relative to the posts 35.

The numeral 92 indicates a closure or panel which is hingedly connected as at 164 to the lowermost section 93 of each door 60, and the closure 92 is mounted for movement into and out of opened and closed relation with respect to an enlarged rectangular opening 103 in the door section 93.

A locking mechanism 94 is provided for the closure 92, and the locking mechanism 94 embodies an angle iron or bar 95 which has an upstanding standard 96 secured thereto or formed integral therewith intermediate the ends thereof. The standard 96 is provided with a yoke 97 that is U-shaped, FIGURE 11, and the yoke 97 includes portions 98, 99 and 100, and portions such as the portions 98 and 100 are provided with apertures or openings 101 and 102 therein. The numeral 104 indicates a latch which is pivotally connected to the closure 92 by means of the pivot pin 105, and a spring member 106 is arranged in engagement with the latch 104 for normally urging or biasing the latch 104 in a counter-clockwise direction, FIGURE 4. There is provided on the upper end of the latch 104 a transverse lip 107, and the numeral 108 indicates an L-shaped body piece which includes portions 109 and 110 that are arranged at right angles with respect to each other, and these portions 109 and 110 are provided with openings 111 and 112 respec-

tively. These openings 111 and 112 are adapted to register with the openings 101 and 102 when the parts are in a position such as that shown in FIGURE 4 so that a conventional lock or seal can be extended through these registering openings in order to prevent accidental movement of the latch 104 or in order to prevent unauthorized opening of the closure 92.

Depending from the bar 95 and secured thereto or formed integral therewith is a plurality of spaced parallel keepers 113, and bearings 114 slidably support the keepers 113. The bearings 114 have their ends affixed as at 116 to the closure 92, and each bearing 114 further includes an intermediate portion 117 that has the keeper 113 arranged in slidable engagement therewith.

There is also provided bearings 118 for the outermost keepers 113, and the bearings 118 have their inner ends 119 affixed as at 120 to the closure 92, and the bearings 118 include portions 121 that engage the end-most keepers 113, FIGURE 4.

There is also provided other bearing units which are indicated generally by the numeral 122, and the bearing units 122 have their inner ends 123 fastened as at 124 to the closure 92, and the bearing units 122 include intermediate portions 125 which have the keepers 113 slidably engaging the same, and the outer end portions 130 of the bearing units 122 are provided with slots 126 for selectively receiving retainers or hasps 127, and the hasps 127 are suitably affixed to the door section 93. Removable pins 128 are adapted to extend through the hasps 127 so as to provide an additional locking feature for the closure 92, and a line or short piece of rope 129 may be provided for anchoring each pin 128 to the door section 93 whereby the lines 129 will help prevent accidental loss of the pins 128.

A guide plate 131 is connected to the closure 92, and the numeral 132 indicates handle elements which are connected to the lower portion of the closure 92, and these handle elements 132 are adapted to selectively engage hooks 133 on a section of the door 60 so that with the handle elements 132 arranged in engagement with the hooks 133, the closure 92 can be held in an open position as desired or required.

There is further provided a manually operable actuating mechanism for the locking device 94, and this actuating means is shown in FIGURE 4 and FIGURE 7 for example. The actuating mechanism comprises a crank 134 which embodies a first portion 135 and is rotatably supported by bearings 136, and the bearings 136 are suitably affixed to the closure 92. The crank 134 further includes a second portion 137 which is arranged at right angles with respect to the first portion 135, and the crank 134 also includes a third portion 138 which is arranged at right angles with respect to the portion 137, and the portion 138 terminates in a fourth portion 139. The numeral 140 indicates a manually movable lever which is swivelly connected to the fourth portion 139 of the crank 134. A clip or bracket 141 is affixed to the closure 92 for selectively receiving the lever 140 when the parts are in the position shown in FIGURE 4 for example. A bracket 142 receives the portion 137 of the crank 134 when the parts are in the position of FIGURE 4. It is to be noted that an end portion 143 of the lever 140 is mounted for movement into and out of engagement with the bar 95 in order to provide a means for moving the lower ends of the keepers 113 into or out of engagement with openings 144, and the openings 144 are arranged to receive the lower ends of the keepers 113. The openings 144 are suitably spaced or positioned in horizontally disposed base pieces or plates 145, and the base pieces 145 are suitably mounted or secured on the floor 31 of the railway freight car 30.

There is further provided a means for shifting the tracks and doors, and this means comprises plates 146 that are L-shaped in cross-section, and the plates 146 are secured to the lower inner surfaces of the posts 35 by

means of securing elements 149. The plates 146 include portions 147 and 148 that are arranged at right angles with respect to each other, and the securing elements 149 extend through the portion 147 and into engagement with the posts 35, as shown in the drawings. First and second studs or pins 150 and 151 are secured as by welding to the lower vertical sections of the tracks 38 and 39, and each stud 150 includes a stem portion 152 as well as an enlarged head 153, while the stud 151 includes a stem portion 154 and an enlarged head 155. The numeral 156 indicates a hand piece or lever which is provided with a slot 157 for the projection therethrough of the stem portion 154 of the stud 151, and an end 158 of the hand piece 156 engages or abuts a portion of a corresponding plate 146, FIGURE 6. By manually moving a hand piece 156 in a clockwise direction, FIGURE 6, the end portion 158 of the hand piece 156 will bear against a portion 159 of the plate 146 so that this will have the effect of moving the tracks and doors so that the doors can be brought tight up against the vertical posts 35 in order to insure that grain or other material being hauled or handled will not accidentally leak or spill out between the doors and posts. After the door has been brought tight up against the posts, a wedge element 160 is positioned on the stud 150 as shown in FIGURE 4 and FIGURE 6 for example, and then manual pressure on the hand piece 156 can be released so that the wedge element will prevent the door from accidentally moving away from the posts. The wedge element 160 is adapted to be retained in its proper position on the stud 150 by means of an arm 161 which is pivotally connected to the plate 146 as at 162.

As shown in FIGURE 1, spaced apart rungs 163 are connected to the door 60.

Referring now to FIGURE 16 of the drawings, there is illustrated a modification wherein the numeral 30' indicates a freight car which has generally the same construction and use as the previously described freight car 30. However, in the freight car 30' the posts 35' are offset relative to the posts 35" and it will be seen that this staggered or offset arrangement of the posts will still permit the door construction of the present invention to be utilized and for example the freight car 30' may include side walls 32' which have openings that are not opposite each other as in the case of the device shown in FIGURE 2 for example. Thus, the tracks 38 and 39 are adapted to be staggered as shown in FIGURE 16 when the present invention is being utilized on a modification such as that shown in FIGURE 16, and the operation or use and construction of the device of FIGURE 16 is generally the same as that shown in the previous views such as FIGURE 2.

From the foregoing, it is apparent that there has been provided a door construction which is especially suitable for use with freight cars or the like wherein such cars are being used for hauling or handling bulk material such as grain. While the present invention has been described and illustrated specifically for use with freight cars, it is to be understood that the door construction is applicable to other members such as grain bins, store houses or the like.

With the parts arranged as shown in the drawings, it will be seen that there is provided the pairs of tracks 38 and 39, and these tracks are shiftable or movable. Thus, the tracks 38 include the upper sections 40 as well as the rounded sections 41 and the lower vertically disposed sections 42, and the upper sections 40 of the tracks 38 are slidably connected to the anchor members 46 as for example as shown in FIGURE 9. The anchor members 46 are adapted to be secured as at 52 to the cross-piece 37 so that the anchor members 46 will remain stationary. However, the portions 43 of the anchor members 46 are provided with slots 49 whereby securing elements 50 can extend through these slots 49 and into engagement with the upper sections 40 of the tracks 38 and

due to the provision of the slots 49, the pins or securing elements 50 can shift back and forth in the slots 49 in order to permit the necessary or desired movement of the upper ends of the tracks 38. In addition, the clips 58 on the support member 53 provide a slidable support for the upper sections 40, and the support member 53 is adapted to be suspended from the top of the freight car 30 as for example by means of the hangers 55. The lower ends of the tracks 38 are provided with the apertured lugs 165, and these lugs 165 engage the pins 91, and the pins 91 are supported by the U-shaped base members 88, the base members 88 being secured to the lower inner portions of the posts 35 and this construction serves to insure that the tracks can shift or move to the desired location.

Similarly, the other pair of tracks 39 are slidably supported, and the tracks 39 have their upper sections 43 slidably supported by the brackets 59 on the support member 53. The lower vertical sections 45 of the tracks 39 are movably supported by means of apertured lugs 165 slidably or adjustably engaging pins 91 on base members 88 in the same manner as described in connection with the slidable supports for the lower ends of the tracks 38.

In order to adjust or move the tracks, there is provided 25 the hand piece 156 which are arranged as shown in FIGURE 6 for example. Thus, to move the tracks to a position such as that shown in FIGURE 6 so that a door 60 is tight against the posts 35, the hand piece 156 is moved in a generally clockwise direction from right to 30 left in FIGURE 6 and since the stud 151 is connected to the hand piece 156, then with the inner end of the stud 151 secured to the track section 45 or 42, it will be seen that with the end 158 of the hand piece 156 bearing against the portion 159 of the plate 146, that this manual 35 movement of the hand piece 156 will cause the tracks to be moved or pulled towards the plate 146. Since the rollers 86 of the doors 60 are arranged in engagement with the tracks, it will be seen that this movement of the tracks by the hand piece 156 will cause the doors to likewise be moved so that as for example the doors can be 40 moved tight up against the vertical posts in order to prevent leakage or wastage of grain or the like. The plate 146 is suitably secured to a corresponding post 35, and after the track and door has been pulled tight as shown 45 in FIGURE 6, a wedge element 160 is adapted to be arranged on the stud 150 and then manual pressure on the hand piece 156 can be released and the wedge element 160 will maintain the door in its desired position tight against the posts 35. The pivotally mounted arm 161 can be 50 arranged as shown in FIGURE 4 for example so that the wedge 160 will be maintained in engagement with the stud 150. When the wedge element 160 is to be removed, the arm 161 can be pivoted on its pivot pin 162 to an out 55 of the way position so as to permit removal of the wedge element 160 as for example when the doors are to be moved inwardly away from the posts 35.

Each of the doors 60 includes a plurality of sections 61 which are hinged together as at 62 so that the doors can travel through actuated paths as for example the door 60 shown in the upper right portion of FIGURE 2 can bend at the hinges 62 as for example when the door is moving in the vicinity of a rounded section such as the section 44 or section 41 in order to insure that there will be no binding. The doors 60 are connected to the tracks 65 by means of the brackets 87 which have the rollers or wheels 86 thereon, and the rollers 86 are mounted for travel in the U-shaped tracks 38 and 39 so that the doors can be readily positioned or moved to the desired location.

70 There is further provided a means for raising and lowering the doors, so that the doors 60 can be raised or lowered as desired or required and this raising and lowering mechanism includes the pair of winch and cable mechanisms indicated by the numeral 69 and shown in detail 75 in FIGURES 14 and 15. By manually turning the hand

wheel 71, the shaft 72 will be turned, and since the gear 73 on the shaft 72 meshes with the gear 74 on the tubular member 75, it will be seen that this rotation of the hand wheel 71 will rotate the tubular member 75 so as to turn or rotate the drums 64, 65, 67 and 68. The cables 63, 63', 66 and 66' are trained over these drums respectively so that with these cables fastened as at 77 to the doors, it will be seen that by manually turning the hand wheel 71 the door can be raised or lowered since the cables will exert the required pressure to move the door in the proper direction. By manually turning the wheel 71 in one direction, the door will be lowered, and by turning the wheel 71 in the opposite direction the door will be raised. The dog 83 is urged into engagement with the gear 78 on the tubular member 75 by means of the spring 84 so that this dog functions as a lock in order to prevent accidental shifting of the winch mechanism, and when the winch mechanism is to be actuated, the dog can be manually moved away from the gear 78 in order to permit rotation of the tubular member 75 by the hand wheel 71 as previously stated.

By raising or lowering the doors, the openings 33 can be exposed or covered as desired so that grain can be placed in or removed or held in the freight car as desired, depending upon the position of the doors.

Each door 60 further includes a closure 92 in the lower portion thereof, and this closure 92 is hingedly connected to a section 93 of the door by means of a hinge 164, and by pivoting the closure 92 on the hinge 164 to a raised position, and opening 103 can be exposed so that grain can be removed through such an opening 103 for any desired purpose. The locking mechanism 94 is provided for selectively maintaining the closure 92 in closed position, and this locking mechanism 94 includes the movable or shiftable bar 95 that has the keepers 113 affixed thereto, and the lower ends of the keepers 113 are mounted for movement into and out of engagement with openings 144 and base pieces 145 so that for example with the parts in the position of FIGURE 4, the lower ends of the keepers 113 are engaging the openings 144 so that pivotal movement of the closure 92 on an axis extending through the hinge 164 will be prevented. However, when the bar 95 is moved upward slightly the keepers 113 will also be moved upward so that their lower ends will clear the openings 144 so that the closure 92 can be opened, after the other parts have been unlatched. When the closure 92 is moved to opened or raised position, the handles 132 are adapted to engage the hooks 133 so as to retain the closure in opened position.

The keepers 113 are arranged in slidable engagement with bearings 118 and 122 as well as with bearings 114, and the bearings 122 include inner end portions 123 which are secured as at 124 to the closure 92. The bearings 122 further include outer end portions 130 which are provided with slots 126 for the projection therethrough of hasps 127 whereby pins 128 can be extended through such hasps when the parts are in the position of FIGURE 4 in order to help maintain the closure in locked position. By removing the pins 128 from the hasps 127, the end portion 130 will be able to move away from the corresponding hasp 127 as for example when the closure is being moved to open position.

The standard 96 is secured to or formed integral with the bar 95, and the standard 96 carries the L-shaped body piece 108 which is adapted to coact with the yoke 97. For example when the parts are in the position of FIGURE 4, the spring pressed latch 104 will be urged in a counter-clockwise direction by means of the spring member 106, so that the L-shaped body piece 108 will overlie a portion of the yoke 97 and the portion 109 of the body piece 108 will be arranged over the portion 98 of the yoke 97 so that upward movement of the standard 96 and locking bar 95 will be prevented. In this position

the latch 104 is conveniently held behind the member 131. The registering openings 111 and 101 and 112 and 102 may receive a portion of a conventional padlock or car seal so as to prevent unauthorized movement or actuation of the locking mechanism. By pivoting the latch 104 in a clockwise direction, FIGURE 4, the body piece 108 will move out of the path of the yoke 97 so that the locking bar 95 can be moved upwardly, and after this bar and its associated parts have been raised or moved upwardly, pressure on the latch 104 can be released so that the spring 106 will urge the latch 104 in a counter-clockwise direction so that the portion 109 will be below the portion 99 in order to selectively maintain the standard and locking bar in raised position.

There is also provided a manually operable means for facilitating the movement of the locking bar 95 and this means comprises a lever 140 which is swivelly or pivotally connected to the portion 138 of the crank 134. The lever 140 is adapted to have its end portion 143 arranged in engagement with the upper or lower portion of the bar 95, and the crank 134 is swivelly supported by means of the bearings 136 so that the crank 134 functions as a fulcrum for the lever 140. Thus, to lower the locking bar 95, the parts are arranged as shown in FIGURE 7 wherein the end portion 143 engages the upper portion of the bar 95 and then by manually moving the lever 140 in a clockwise direction, FIGURE 7, pressure will be applied by the end 143 downward on the bar 95 so that for example the bar 95 can be moved downwardly and wherein the keepers 113 can be moved down into engagement with the openings 144 so that the mechanism 94 can be locked. Similarly, due to the swivel connection between the lever 140 and the crank 134, the end 143 can be arranged in engagement with the lower portion of the bar 95 so that an upwardly directed force can be applied to the bar 95 in order to facilitate upward movement of the bar 95 and upward movement of the parts such as the keepers 113.

The parts can be made of any suitable material and in different shapes or sizes.

It will be seen that there has been provided a grain door for a railroad freight car to prevent the grain from accidentally spilling out of the doorway such as the doorway or opening 33. In use, it is to be noted that cars of grain have to have samples of grain taken from the car for inspection and grading purposes and a grain door is left approximately three feet from the top of the door space to permit men to climb inside the car and get samples of grain.

Temporary grain doors that are destroyed or removed from the car each time a load of grain is unloaded makes it very expensive and costs millions of dollars each year and the railroad freight car grain door of the present invention has been provided as a much needed device for loading and unloading grain or other commodities that are hauled in railroad freight cars in a safe and efficient and economical manner and wherein the grain door will be a permanent part of the car and stay with the car at all times and when the door is not needed, it is up at the top of the inside of the car on tracks out of the way when the car is used for merchandise, machinery or freight of any description other than grain or such commodities.

Then, any time that the car is needed for grain or such commodities, the grain door is ready for instant use and it is only necessary to lower the door into place and it is ready for service. The grain door has the winch for lowering and raising the same quickly and easily and the dog 83 engages the gear 78 so that there is provided a locking device for holding the door partly open or in any desired position. Each door consists of a series of sections hinged together. When the grain or commodity is loaded in the car there is a considerable amount of pressure and weight against the grain door and the door cannot be raised with such weight against it so that in the

lower portion of the door there is provided the dump gate or closure 92 which opens independently of the remaining portion of the door and when this gate or closure 92 is opened it permits the grain to flow freely out of the car into the grain pit below so as to relieve the pressure of the grain against the grain door and then the entire door can be raised or easily opened with the winch or raising device. The entire load can be unloaded through the opening 103 if desired so that it is not necessary to open the entire door.

The tracks are mounted as previously described so that the grain cannot get in the rollers 86 whereby there will be no interference with normal functioning or movement of the door. The doors are adapted to fit tight against the posts and lining of the car to prevent the grain from leaking out and this is accomplished by means of the floating track or mounting which permits the tracks to float or move back and forth slightly so that there will be just enough slack to release the pressure of the door from the door posts or lining to provide clearance so that the door can be raised, and the door and tracks move forwardly slightly just sufficient to bring the door tight against the door posts and lining to prevent the grain from leaking around the door. The previously described mechanism is provided for operating the door and moving the track and door back and forth in a highly convenient manner.

It is to be noted that two grain doors 69 are needed for each freight car, and one is arranged on each side of the car and the doors operate in the U-shaped channel iron tracks 38 and 39, and one set of tracks 38 has its upper portion or section 49 above the upper section 43 of the other tracks 39 and this construction permits the doors to operate or move without interfering with each other and when the doors are not needed they are in the raised position in the upper sections of the tracks near the top of the car out of the way. The tracks only need move a short distance in order to accomplish the floating action previously described.

The anchor members 46 can be fastened to the cross-piece 47 or else they can be connected to the lining 166 of the freight car.

The openings 144 may be cut through the metal threshold plate or metal strip 145 that is over the floor 31 in the doorway 33 that the dump door keeper bars 113 pass through.

Some freight cars are such that the doors are not exactly opposite each other and for such freight cars a hinge brace or support can be attached to the roof of the car to support the one track that does not contact the wall or door posts than it ordinarily would if the doors were opposite.

The winch mechanism 69 provides a safe and easy lifting device for the grain door and the locking dog 83 will hold the door open or partly open or in any desired position. This dog can be released when the doors are to be moved and the spring member 84 applies pressure to the dog 83 so that accidental shifting thereof is prevented.

The cables are arranged so that when a door is in downward position, two of the inside cables are already wound on a set of drums and then when the two outside cables start winding up, the two inside cables start unwinding so that when the door is in the up position the hand wheel can be turned in a desired direction and then the door can be lowered so that either or both doors can be raised or lowered, and the winch mechanism 69 is adapted to be attached to the sills of the railroad freight car under the floor near the center of the door, and braces can be used wherever desired or required.

In addition, the doors of the present invention can be used for grain bins or buildings, as well as for railroad freight cars.

As previously stated there is one winch mechanism 69 for each door 69 and each winch mechanism 69 has one

hand wheel 71, and the hand wheel 71 is affixed to the shaft 72, and likewise the gear 73 is affixed to the shaft 72 the shaft 72 as well as the tubular member 75 being rotatably supported by panels such as the panels 81 and 82 and these panels in effect may be a U-shaped frame which supports the mechanism of the winch. The numeral 76 indicates the bottom portion of the U-frame, and this U-shaped frame is indicated generally by the numeral 80, FIGURE 14. The numeral 81 indicates the outside panel of the U-frame 80, and the numeral 82 indicates the inside panel of the U-frame 80. The numeral 63 indicates an inside cable, and the numeral 66 indicates an outside cable.

Similarly, the numerals 63' indicates an inside cable and the numeral 66' indicates an outside cable, and the outside cable winds the door up and is trained over a drum, and the inside cable may be said to wind the door down and is also trained over a drum as previously stated.

The member 131 is a guide plate near the top of the latch device 104 and standard 96 to maintain the parts lined up in place and the guide plate 131 can be secured to the closure 92 with bolts or the like.

The wedge element 160 is adapted to have a chain 160' attached thereto, FIGURE 4, so that the wedge element 160 will not accidentally become lost.

The shaft 72 of the winch mechanism 69 has a square end portion 79 extending through the hub of the hand wheel 71 several inches so that a power motor or the like with a square socket can be used if desired for operating the winch mechanism.

As shown in FIGURE 2, holes or openings 25 may be arranged in the front side of the tracks so that a pin such as the pin 24 can be extended through these holes 25 in a downward slanting position just below the bottom rollers 86 when the door is in fully raised position and this will function as a safety feature to prevent the door from falling if a cable breaks, and this safety pin 24 is adapted to be secured to the door posts with a chain such as the chain 23 so that loss of the pin 24 will be prevented.

As shown in FIGURE 5 for example, shims 22 are adapted to be placed between the door posts 35 and the member 83 so that the tracks can be positioned the same width apart at both the bottom and the top for proper operation of the rollers 86 and carriers 87.

With further regard to the winch, it is to be noted that when the door is in a downward position two of the cables are already wound on the drums, and when the other two cables start winding up, the other two cables start unwinding, and this cycle of operation is repeated as the winch is actuated.

Any kind of material can be used and for example if the parts are made of wood, the wood can be reinforced with metal plates, braces or the like, and if made of metal it can be corrugated or reinforced for strength, and the number of panels can vary as desired or required.

Minor changes in shape, size and rearrangement of details coming within the field of invention claimed may be resorted to in actual practice, if desired.

60. What is claimed is:

1. In a hollow member, a floor, vertically disposed side walls and a top, there being doorway openings in said side walls, vertically disposed posts on opposite sides of said openings, horizontally disposed crosspieces above said posts, first and second pairs of tracks in said hollow member, each of said tracks including horizontally disposed upper sections, intermediate rounded sections and vertically disposed lower sections, the upper horizontally disposed sections of said first tracks being arranged above the upper sections of said second tracks, anchor members affixed to one of said crosspieces, the upper horizontally disposed sections of said first tracks being slidably connected to said anchor members, a support member including a horizontally disposed top portion, hangers connecting the top portion of said support member to the top

of said hollow member, said support member further including vertically disposed depending end portions and horizontally disposed bottom portions, clips depending from the top portion of said support member for slidably supporting the upper sections of said first tracks, brackets on the upper inner ends of the bottom portions of said support member for slidably supporting the upper section of the second tracks, adjustable doors movably connected to each pair of tracks, each of said doors including a plurality of sections hingedly connected together, rollers connected to said doors and engaging said tracks, cables and winches for raising and lowering the doors along the tracks, U-shaped base members secured to the lower inner portions of said posts, pins supported by said base members, and apertured lugs on the lower end portions of the tracks slidably engaging said pins.

2. The structure as defined in claim 1 wherein said hollow member is a railway freight car.

3. The structure as defined in claim 1 and further including a closure hingedly connected to the lowermost sections of each door, and a locking mechanism for said closure.

4. In a hollow member, a floor, side walls and a top, there being doorway openings in said side walls, posts on opposite sides of said openings, crosspieces above said post, first and second pairs of tracks in said hollow member, each of said tracks including upper sections, intermediate rounded sections and vertically disposed lower sections, the upper sections of said first tracks being arranged above the upper sections of said second tracks, anchor members affixed to one of said crosspieces, the upper sections of said first tracks being slidably connected to said anchor members, a support member including a top portion, hangers connecting the top portion of said support member to the top of said hollow member, said support member further including depending end portions and bottom portions, clips depending from the top portion of said support member for slidably supporting the upper sections of said first tracks, brackets on the bottom portions of said support member for slidably supporting the upper section of the second tracks, adjustable doors movably connected to each pair of tracks, each of said doors including a plurality of sections hingedly connected together, rollers connected to said doors and engaging said tracks, cables and winches for raising and lowering the doors along the tracks, base members secured to said posts, pins supported by said base members, and apertured lugs on the lower end portions of the tracks slidably engaging said pins, said hollow member being a railroad freight car, a closure hingedly connected to the lower-most section of each door, a locking mechanism for each closure and said locking mechanism comprising a movable bar adjacent the outer surface of the closure, an upstanding standard affixed to said bar, an apertured lug affixed to said standard, a spring pressed latch pivotally connected to said closure, an apertured body piece carried by said latch for engaging said yoke; a plurality of spaced apart keepers depending from said bar and secured thereto, base pieces on said floor and said base pieces being provided with a plurality of openings therein for selectively receiving the lower ends of said keepers, bearings connected to said closure for slidably supporting said keepers, certain of said bearings including outer end portions which are provided with slots, retainers for projecting through said slots, pins releasably engaging said retainers, and manually operable actuating means for said locking mechanism for said closure.

5. The structure as defined in claim 4 wherein said last named manually operable actuating means comprises a crank adjustably connected to said closure, and a lever 70 swivelly connected to said crank for selectively engaging the bar of the locking mechanism.

6. The structure as defined in claim 4 and further including handle elements connected to said closure, and hooks connected to the door for selectively being engaged by the handle elements to retain the closure in opened position.

7. In a hollow member, a floor, side walls and a top, there being doorway openings in said side walls, posts on opposite sides of said openings, horizontally disposed crosspieces above said posts, first and second pairs of tracks in said hollow member, each of said tracks including upper sections, intermediate rounded sections and vertically disposed lower sections, the upper sections of said first tracks being arranged above the upper sections of said second tracks, anchor members affixed to one of said crosspieces, the upper sections of said first tracks being slidably connected to said anchor members, a support member including a top portion, hangers connecting the top portion of said support member to the top of said hollow member, said support member further including depending end portions and bottom portions, clips depending from the top portion of said support member for slidably supporting the upper sections of said first tracks, brackets on the upper inner ends of the bottom portions of said support member for slidably supporting the upper section of the second tracks, adjustable doors movably connected to each pair of tracks, each of said doors including a plurality of sections hingedly connected together, rollers connected to said doors and engaging said tracks, cables and winches for raising and lowering the doors along the tracks, base members secured to the lower inner portions of said posts, pins supported by said base members, and apertured lugs on the lower end portions of the tracks slidably engaging said pins, said hollow member being a railroad freight car, a closure hingedly connected to the lowermost section of each door, a locking mechanism for each closure and said locking mechanism comprising a movable bar adjacent the outer surface of the closure, an upstanding standard affixed to said bar, an apertured lug affixed to said standard, a spring pressed latch pivotally connected to said closure, an apertured body piece carried by said latch for engaging said yoke; a plurality of spaced apart keepers depending from said bar and secured thereto, base pieces on said floor and said base pieces being provided with a plurality of spaced apart openings therein for selectively receiving the lower ends of said keepers, bearings connected to said closure for slidably supporting said keepers, certain of said bearings including outer end portions which are provided with slots, retainers for projecting through said slots, pins releasably engaging said retainers, and manually operable actuating means for said locking mechanism, said manually operable actuating means comprising a crank adjustably connected to the closure, a lever swivelly connected to said crank for selectively engaging the bar of the locking mechanism, handle elements connected to said closure, hooks connected to a section of the door for selective engagement by the handle elements, and manually operable means for shifting the tracks and doors, said last named means comprising plates secured to said posts, first and second studs affixed to said tracks and said first stud extending through said plate, a hand piece having said second stud projecting therethrough and said hand piece engaging said plate, a wedge element releasably mounted on said first stud, and a pivotally mounted arm pivotally connected to said plate for selectively engaging said wedge element.
